UNITED STATES PATENT OFFICE.

PHILIP T. DODGE, OF NEW YORK, N. Y.

LINOTYPE-MACHINE.

SPECIFICATION forming part of Letters Patent No. 605,701, dated June 14, 1898.

Application filed July 14, 1897. Serial No. 644,503. (No model.)

To all whom it may concern:

Be it known that I, PHILIP T. DODGE, of New York, county of New York, and State of New York, have invented a new and useful Improvement in Linotype-Machines, of which the following is a specification.

In the use of slugs or linotypes such as are commonly produced by the Mergenthaler linotype-machine it is frequently necessary to keep the "forms" standing for long periods of time, and as these slugs are commonly made solid—that is to say, without openings or recesses of any kind in them—a large investment is necessary for metal. The object of my invention is to reduce the consumption of metal by producing slugs with cavities in the base; and to this end the invention consists in an improvement in the mold and ejecting devices adapted for use in the Mergenthaler and analogous machines.

Referring to the drawings, Figure 1 represents in perspective a slug produced by my means. Fig. 2 is a perspective view of the mold in which the slug is formed, together with the ejector-blade for removing the slugs. Fig. 3 is a cross-section of the mold on the correspondingly-numbered line of Fig. 2. Fig. 4 is a longitudinal section through the mold from end to end on the correspondingly-numbered lines of Figs. 2 and 3.

The slug represented in Fig. 1 is a solid cast-metal body type high and provided on its upper edge with a series of type characters adapted to print an entire line. It differs from the slug commonly in use only in that it is provided in the base with cavities *a*. These cavities may be varied in form and number at will, provided only there is sufficient metal left in the body and base of the slug to give proper support to the type at the surface in order that they may not sink under the pressure applied to them when in use.

The slugs as above described cannot be produced in molds of the ordinary form, which have an unobstructed slot or opening from one end to the other, so that a solid ejector-blade may be passed therethrough.

In order to produce the improved slug, I provide the solid slotted mold *B*, which in all other respects is of ordinary construction, with two internal blocks or filling-pieces *b*, which are pinned fast or otherwise secured in

place. These blocks stand flush with the mold on the rear side and extend through it but part way to the front, as plainly shown in Figs. 3 and 4. When, therefore, the mold is filled with molten metal, as usual, to produce the slugs, the blocks *b* form the cavities in the base, while the front or top edge of the slug, bearing the type characters, is continuous and unbroken. The mold thus formed presents a smooth unbroken rear face and serves to hold or support the slug while the trimming-knife is passing over its base from one end of the mold to the other, as usual.

In order to effect the ejection of the slugs, I employ an ejector-blade which is slotted or forked longitudinally, so that it presents a number of arms to pass through the mold. The ejector may be made, as shown, of a single plate or of a series of separate blades or arms, as indicated by the dotted lines in Fig. 2.

It will be understood that the mold and ejector herein shown are adapted for use in the ordinary Mergenthaler linotype-machine in the same manner that the ordinary molds and ejectors are used therein and that in all other respects the machine may be of the customary construction.

The essence of my invention resides in the mold adapted to form cavities in the base of the slug and in an ejector having two or more arms to effect the delivery of the slugs.

I am aware that in the so-called "Rogers typograph-machine" a mold adapted to open and close was recessed at the base to admit the conical mouth of the melting-pot, which produced a central cavity in the base of the slug. Such construction is not, however, applicable in the Mergenthaler machines or analogous machines using solid molds. I believe myself to be the first to incorporate in the linotype-mold parts or members adapted to produce cavities in the base of the slug and the first to combine with a solid linotype-mold having a plurality of openings through its base an ejector having a corresponding number of fingers or branches adapted to enter the mold from the rear and eject the slugs from the front.

Having thus described my invention, what I claim is—

1. A linotype-mold having at the front an unobstructed slot or opening, and at the rear

one or more filling-pieces forming part thereof to produce cavities in the base of the slug or linotype.

2. A linotype - mold having a continuous slot or opening at its front to produce a slug with an unbroken face, and having the back closed for a portion of its length with two or more openings for the admission of an ejector.

3. A linotype-mold containing an elongated slot or mold proper, its face adapted to coöperate with a series of matrices, and its rear side having a plurality of openings, in com-

bination with an ejector, disconnected from the mold and having a plurality of fingers or blades adapted to enter and withdraw from said mold-openings, substantially as described and shown. 15

In testimony whereof I hereunto set my hand, this 2d day of July, 1897, in the presence of two attesting witnesses.

PHILIP T. DODGE.
